UNITED STATES PATENT OFFICE.

WERNER F. ROTHERMUND, OF BROOKLYN, NEW YORK, ASSIGNOR TO THOMPSON & NORRIS COMPANY, OF BROOKLYN, NEW YORK.

LOCK FOR CARTONS.

Application filed January 6, 1922. Serial No. 527,527.

To all whom it may concern:

Be it known that WERNER F. ROTHERMUND, a citizen of the United States, and a resident of New York city, borough of Brooklyn, in the county of Kings and State of New York, has invented certain new and useful Improvements in Locks for Cartons, of which the following is a specification.

My invention relates to locks and is especially adapted for use as a lock for a carton of the card board type.

The object of my invention is to provide a lock that can be made of sheet material, such as sheet iron or brass, and that when in use will lie practically flat on the carton.

A further object is to provide a lock that may be attached to the carton flaps when the carton is in its knock-down condition and after the carton is folded into box form, may be locked and cannot be thereafter unlocked without breaking.

A further object is to provide a lock of this character with means whereby the lock can be accurately positioned on the carton flap to insure the interlocking parts coming together accurately when the flaps of the carton are folded to close the carton.

Referring to the drawings which form a part of this specification;

Figure 1 is a perspective view of a carton with a lock thereon illustrative of my invention.

Figure 2 is a plan view of a lock member shown partly in section to disclose the catches of the lock.

Figure 3 is a plan view of the interlocking member which engages the member shown in Figure 2.

Figure 4 is a longitudinal sectional view on line 4—4 of Figures 2 and 3 as it appears when the members are in locked relation on the flaps of a carton.

Figure 5 is a perspective view of the lock with the parts in locked relation and showing the tangs by which the lock is secured to the carton.

A, indicates a carton having flap cover portions A'—A' respectively, which are hinged at B—B respectively.

C and C' indicate the two interlocking portions of the lock, each being made in a single integral piece, stamped and folded by suitable dies into the forms shown.

The lock portion C is first stamped from a sheet to provide the required form of blank

and is then folded to provide the upper and lower plates D and E respectively which are spaced apart a distance corresponding to the thickness of the sheet from which the lock is made to provide a space F into which the leaf G projects and is held by the catches H—H—H respectively, which enter the openings I—I—I respectively, formed in the leaf G. G.

The catches H, H, etc., act as springs, being depressed by the end of the leaf G when same is forced into the space F, and snapping upward into the openings I—I, etc., when the same are brought into position for engagement so that the edges J—J—J respectively abut the ends K—K—K respectively of the spring catches H, as will be readily understood.

The inner end of the lower plate E is bent downward at a right angle to the plane of the plate to form a flange L which abuts the end of the flap A' and by this means the lock portion C is positioned accurately on the flap. The lock portion C' may be provided with a raised rib M which serves to limit the travel of the leaf G beyond a predetermined position in the portion C and also serves to guard the edge N thereof. Both portions of the lock are provided with tangs O—O—O, etc., by means of which the lock portions are secured to the carton, and on the portion C they overlap the space F and prevent the plates D and E from being forced apart after the lock portion is clamped on the carton. The lower plate E projects beyond the upper plate D as clearly shown at P in Figure 2 so that the end of the leaf G may rest thereon when the flaps A' are folded downward in the act of closing the carton, and serve as a guide for the leaf in entering into locking engagement.

It will be seen that after the carton is once locked it cannot be opened without injury either to the lock or carton, and therefore a person receiving the carton may easily determine whether the carton has been opened or tampered with.

Having thus described my invention I claim as new;

1. A lock of the character described comprising a member comprising spaced plates one of which has resilient portions extending into the space between said plates, a second member having slots therein adapted to advance between said spaced plates, said

slots being adapted to be engaged by said resilient portions.

2. A lock comprising one member comprising a sheet of metal bent upon itself so that the space between the bent portions is substantially the thickness of the sheet, resilient projections formed on one of said bent portions and extending into said space, a second member of sheet metal of substantially the same thickness as said first member

and adapted to be inserted in said space, said second member having slots therein adapted to cooperate with said resilient projections.

Signed at New York, in the county of New York and State of New York, this 4th 15 day of November, A. D. 1921.

WERNER F. ROTHERMUND.

Witness:

GEORGE SCULATT.
